(57) **CLAIM**

We claim the ornamental design for the centering dovetail vise, as shown and described.

DESCRIPTION

FIG. 1 is a perspective view of a first embodiment of the centering dovetail vise, showing our new design:

FIG. 2 is another perspective view thereof;

FIG. 3 is a front view thereof;

FIG. 4 is a back view thereof;

FIG. 5 is a top view thereof;

FIG. 6 is a bottom view thereof;

FIG. 7 is a side view thereof; and

FIG. 8 is another side view thereof, showing the side opposite that shown in FIG. 7.

FIG. 9 is a perspective view of a second embodiment of the centering dovetail vise:

FIG. 10 is another perspective view thereof;

FIG. 11 is a front view thereof;

FIG. 12 is a back view thereof;

FIG. 13 is a top view thereof;

FIG. 14 is a bottom view thereof;

FIG. 15 is a side view thereof; and,

FIG. 16 is another side view thereof, showing the side opposite that shown in FIG. 15.

The broken lines in the drawings depict unclaimed portions of the centering dovetail vise only and form no part of the claimed design.
